(57) **CLAIM**

We claim the ornamental design for a crown channel for a golf club head, as shown and described.

DESCRIPTION

FIG. 1 is an isometric view of a crown channel for a golf club head showing our new design;

FIG. 2 is a rear elevation view thereof;

FIG. 3 is a top plan view thereof;

FIG. 4 is a heel side elevation view thereof; and,

FIG. 5 is a toe side elevation view thereof.

The broken lines are for illustrative purposes only and form no part of the claimed design.
